FIG. VII.

UNITED STATES PATENT OFFICE.

JOHN A. HOLMQUIST, OF WOODLAWN, PENNSYLVANIA.

WIRE-FENCE MACHINE.

1,378,958.

Specification of Letters Patent. Patented May 24, 1921.

Application filed March 22, 1920. Serial No. 367,707.

To all whom it may concern:

Be it known that I, JOHN A. HOLMQUIST, residing at Woodlawn, in the county of Beaver and State of Pennsylvania, a citizen 5 of the United States, have invented or discovered certain new and useful Improvements in Wire-Fence Machines, of which improvements the following is a specification.

10 My invention relates to improvements in wire-fence machines, such as the Bates machine (Bates Patent, No. 577,639) and the Denning machine (Denning Patents, Nos. 816,538 and 900,490), in which, to a succession 15 of parallel strand wires, stay wires of short length are applied, spanning the intervals between adjacent strand wires, and having their ends coiled about the strand wires. The invention concerns particularly the in- 20 strumentalities for handling the stay wires.

I shall illustrate and describe my invention applied to a machine of the Denning type; but, from what has just been said, it will be understood that it is applicable to machines 25 of any type whatever having the general characteristic indicated above.

In the accompanying drawings, Figure I is a view in side elevation of a machine of the Denning type in which my present invention 30 is embodied; Fig. II is a view to larger scale and in vertical transverse section, showing the stay-handling instrumentalities of this machine assembled with the other parts; Fig. III is a plan view, and to still larger 35 scale, of the table of the machine showing certain of the stay-handling instrumentalities; Fig. IV is a view in vertical transverse section, on the plane indicated by the line IV—IV, Fig. III; Fig. V is a view in side 40 elevation of the guide (a detail shown in Fig. III), looking into its open mouth; and Figs. VI and VII are views in end elevation, and to equal scale with Fig. III, of the instrumentality termed the "pusher," together 45 with certain operating parts, while other parts are here, for clearness of illustration, omitted.

The typical Denning machine is characterized by this: that both strand-wire feed and 50 stay-wire feed are continuous; and the fence-forming instrumentalities act upon the material and form it into fence, under that fundamental condition. The machine here shown is so far a modification of the Denning machine that the strand wires, while they are, as with Denning, drawn through

the machine by the constant tension of a uniformly turning clamping-drum, are, in that portion of their path where the stay wires are attached, alternately accelerated 60 and retarded in their advance. This feature is more fully explained in my companion application, Serial No. 367,704. The stay-wire feed, however, is, as with Denning, continuous through the cutting mechanism. 65

Referring particularly to Fig. II, the path of the strand wires is indicated by the dotted line *a*, and an arrow upon the line indicates the direction of advance. These wires (there are several, abreast) pass up through the 70 coolers 1 over a roller 3, and thence to the clamping cylinder 2 (see Fig. 1). From the clamping cylinder, it will be understood, the finished fence passes to a suitably placed reel. 75

The path of advance of the stay wires is indicated in Fig. II by the dotted line *b*, and their direction of advance also is indicated by an arrow point. It will be understood of the stay wires also that there is a succession of the lines of feed, corresponding in 80 number to the inter stay wire spaces, and arranged side by side. The stay wire advances in continuous length, from a suitable source of supply, through a guide tube 50. It is impelled in its advance by a pair of rolls 51, 52, 85 which engage it between them. One of these rolls, 51, is positively driven, and the driving connections from the main driving shaft 4 of the machine to the shaft of roll 51 may be of any convenient particular form. The roll 52 90 turns idly in its bearings and is spring-backed, to hold the wire yieldingly, and yet to impart to it the driving impulse. At its upper end the guide tube 50 makes a turn, 95 and the stay wire is delivered, through an orifice in a block 53, in a direction transverse to the general direction of strand-wire and stay-wire feed and diagonally between adjacent strand wires. These features, sufficiently indicated in the drawings, are shown 100 and described at greater length in the Denning patents already alluded to.

In the machine of the Denning Patent No. 816,538, the stay wire passes through an orifice 84 in the stationary block 83 and a 105 flying shear 86, passing across this orifice at regularly succeeding intervals, cuts stay wires of predetermined length from the continuously advancing length of stay-wire feed. The flying shear of the Denning patent is rotatable, being carried on the disk 88 110 mounted on shaft 27. In place of such a ro-

tary disk, I employ a reciprocating knife 54. As with the cutter of the Denning patent, it is narrow in that portion which traverses the orifice in block 53, so that the time of obstruction of the orifice is reduced to a minimum. It is the forward edge—that is, the right-hand edge, as shown in Figs. VI and VII—of knife 54 which is the cutting edge. This knife 54, which as has been said is reciprocating, is so mounted that on its forward stroke its cutting edge passes across the orifice in block 53 (and so block 53 and knife 54 together constitute a pair of shears), but on its reverse and backward stroke it is clear of the orifice, nor does it make contact with or in any way interfere with the further advance of stay-wire through the orifice. This end is accomplished by causing the knife to swing as it reciprocates, from one plane to another, so that it drives forward and recedes in another plane. Fig. VII shows the cutter in dotted lines in its retracted position. From that position it advances to the full-line position shown in Fig. VI, to effect the cutting of the individual stay wire from the advancing stay-wire feed, indicated at 55. In retraction the knife is raised, as is shown in full-line position in Fig. VII, so that it passes back from the full-line position shown in Fig. VI without obstructing the orifice or interfering with the advance of the stay-wire feed.

35. The reciprocating movement, to effect the advance of the knife from the dotted-line position shown in Fig. VII to the full-line position shown in Fig. VI and back again, is effected by mounting the succession of 40 knives (one for each stay-wire feed) in a slide, and causing this slide to reciprocate. The slide is composed of the blocks 56, 57, and reciprocation is imparted to it from a shaft 58 by means of a pair of arms 59 pivoted to the slide, one at each end thereof, and reciprocated through eccentric engagement with shaft 58 (see Fig. II). Shaft 58 may be rotated through suitable connections (not shown), in unison with the main driving 45 shaft 4 of the machine. Movement of the knife from one plane to another, according as it reciprocates to and fro, is effected by forming the slide of two blocks, 56, 57, in mounting the knives in the upper block, 56, and in making provision that, as the slide reciprocates, the upper, knife-carrying block shall rise and fall, conveniently by swinging or pivoting slightly upon the lower. To this end the two blocks lie normally face to face, held to that position by the spring-backed bolts 64 which extend through enlarged bolt holes in the upper block but are firmly secured against withdrawal from the lower. This construction 55 permits block 56 to rock or tip upon block

57; and, since it is the forward edge of block 56 (that is to say, the right-hand edge, Figs. VI and VII) which rises and falls, the lower rear edge is advantageously rounded, as indicated at 65. End projections upon block 56, preferably taking the form of rollers 60 on projecting shafts, engage a pair of walking beams 61, and, as the slide advances and recedes these rollers roll along the faces of these walking beams. 70 The walking beams themselves swing on suitable pivots, and are controlled in their swinging movement by the springs 62 of bolts 64 which tend to press their left-hand ends downward (Figs. VI and VII), 75 and cams 63 conveniently mounted on the same shaft 58, which at suitable intervals press their right-hand ends downward. It is manifest that suitable shaping of the cams and suitable placing of them upon 80 shaft 58, relatively to the eccentrics already mentioned, will effect the movement desired: namely, a wire-cutting traverse of the knife (from left to right, Figs. VI and VII) in one plane and a reverse traverse in 85 another plane, in which the knife will pass above the path of stay-wire advance and will be free of contact with the stay-wire. 90

Further features of the invention relate to the handling of the stay wire after it has 95 been cut off. Explanation has been made, that the stay wire is projected from the guide in a direction transverse to the general direction of strand-wire and stay-wire feed and diagonally between adjacent strand 100 wires. This is indicated in Fig. III, where a succession of stay wires *b'* are shown, advancing diagonally between adjacent strand wires *a'*. As here shown the now advancing ends of the stay wires are not yet long 105 enough for cutting off and the knives 54 are still retracted. Between the paths of adjacent strand wires *a* is a succession of stay-wire guides. Each guide consists of three plates: an underlying plate 70, and two 110 smaller and superposed plates 71 and 72 incompletely covering plate 70. Plate 71 is bolted in stationary position upon plate 70, and plate 72 is pivoted upon plate 70 and held by tension of a spring 73 normally in 115 the position shown, with a relatively wide space between its edge and the adjacent edge of plate 71. Even when swung, however, against the tension of spring 73, still the adjacent edges of plates 71 and 72 stand 120 apart. Furthermore, the adjacent edges of plates 71 and 72 may advantageously be formed with an overhang, and thus the three plates 70, 71, and 72 assembled constitute a 125 guide for the advancing stay wire; a guide, be it observed, whose passageway is widest at the mouth—where advantageously the corner is rounded to form a bell-mouth—and a guide whose passageway widens and contracts periodically as plate 72 swings, the 130

greatest variation in width being at a point remote from the mouth.

The forward end of the length of stay-wire, driven by rolls 51, 52, advances 5 through the hole in block 53 and then through the guideway just described—which is then in the wide-open position shown in Fig. III. When the length of stay-wire has advanced so far that its end sufficiently 10 overlaps the strand wire to which it is to be applied, the knife 54 which now is advancing, has reached the hole through block 53 and now cooperates with the block, and, as in a pair of shears, cuts free a stay-wire 15 from the continuous length of stay-wire feed. The now severed stay rests over its medial portion upon the plate 70 while its two ends lie adjacent to and on opposite sides of, but, as will be remarked in studying Fig. III, at some appreciable distance 20 from two adjacent strand wires. At this juncture (or slightly before) the forward advance of the slide 56, 57 brings pusher 74 (which also the slide carries) to bear upon 25 the stay-wire at one end; and then the further advance of the slide and a coincident swing of plate 72 upon its pivot (which plate engages the wire at the opposite end) swing the wire upon plate 70 as upon a ful- 30 crum (and it will be observed in Fig. IV that plate 70 may be arched) and bring its opposite ends to bear against the two strands to which it is to be secured. When the stay has so been swung, the coilers 1 rise and en- 35 gage the stay and coil it by its opposite ends to the strand wires. Meanwhile the slide with its knife 54 and pusher 74 and the plate 72 recede, preliminarily to acting in like manner upon the next succeeding stay.

40 The pusher 74 here first mentioned is a known adjunct of these machines; it may conveniently be, as it here is shown to be, a rigid finger extending from block 56 of the slide already described. Fig. III will show 45 that it acts upon a newly cut stay at a point nearer its center of turning upon plate 70 than the knife 54 which has just effected the cutting. In consequence of this more advantageous position the advance of slide 56 need not be so great as would be the case if 50 the knife 54 were the instrumentality by which the severed stay was pushed to position. In the retraction of the slide the pusher 74 will rise as knife 54 rises and 55 pass back free of contact with the next on-coming stay.

Throughout the foregoing description of the function of the stay-wire guide and its associated parts, I have spoken of stay-wire 60 and guide, knife, and pusher in the singular. It will of course be understood that this has been a matter of convenience, and that in fact, and as the drawings show, these parts are multiplied a number of times in 65 the organization of the machine as a whole.

The reciprocation of knife and pusher has been sufficiently explained; it remains to explain the periodic pivotal movement of plate 72. As has already been said, plate 72 is pivoted to plate 70. The pivot pin is 70 also the securing bolt 75. In a companion application (Serial No. 367,704) I have described the coilers and their mounting. Suffice it here to say of the coilers 1 that, in the course of machine operation, when the 75 moment comes for them to act they rise and, engaging the ends of the stay-wires, coil them about the strand wires. These coilers are borne in a bar 10 and bar 10 rises and descends in a determined periodicity to effect the end just stated. This bar 10 is conveniently equipped with a succession of wedge surfaces 76 properly disposed and placed, so that as bar 10 rises these wedges 80 76 engage plates 72 and swing them on their pivots to perform their stay-wire pushing duty, so that, when the coilers arrive at the point of wire engagement, the stay-wires have come to the point to be engaged. The 85 rise and fall of bar 10 is, as is explained in 90 the companion application referred to, effected by the rotation of shaft 9 which is driven from the main power shaft 4; and the movement of knives and pushers is effected by the rotation of shaft 58, also 95 driven from shaft 4. It is a matter of mere proportioning to effect coincident and correlated operation of these various wire-manipulating parts.

It will be understood that, in the operation 100 of the machine, immediately when the coilers have performed their essential function and begin to recede, the movable plates 72 of the stay-wire guides are released, so that they swing under the impulse of 105 springs 73, and open to allow the strand wires to advance, carrying now the stays which have been secured to them.

As I said at the outset this invention is 110 not limited in its applicability to machines of the Denning type. The essential features of invention are enumerated and characterized in the ensuing claims; beyond these features, the showing of the specification is exemplarily merely, and the details of 115 structure are not to be taken by way of limitation.

I claim as my invention:

1. In a wire-fence machine, in combination with stay-wire feeding mechanism, two knife members, and means for imparting to one of said knife members reciprocation relatively to the other together with movement from one plane of travel to another on the completion of each forward and rearward stroke, substantially as described. 125

2. In a wire-fence machine, in combination with stay-wire feeding mechanism, a tipping slide, a knife borne by said slide, means for reciprocating said slide, and means 130

- coördinated with said reciprocating means for tipping said slide, substantially as described.
3. In a wire-fence machine, in combination with stay-wire feeding mechanism, a tipping slide, a knife and a pusher borne by said slide, means for reciprocating said slide, and means coördinated with said reciprocating means for tipping said slide, substantially as described.
4. In a wire-fence machine, in combination with means for feeding a plurality of strand wires in parallel paths, means for feeding the forward end of a continuous length of stay wire diagonally between two strand-wire paths, a stay-wire guide having a runway of periodically varying width arranged between the two strand-wire paths, and a stay-wire cutter including a knife reciprocable forward and rearward in different planes of travel, substantially as described.
5. In a wire-fence machine, the combination of means for feeding a plurality of strand wires in parallel paths, means for feeding a stay wire transversely of and diagonally between strand wires advancing in the paths defined, a stay-wire guide arranged between the paths of the strand wires and provided with a notch, and means for narrowing and widening the notch intermittently in the operation of the machine, substantially as described.
6. In a wire-fence machine, the combination of means for impelling two strand wires in parallel paths, means for impelling a stay wire transversely of and diagonally between such strand wires, a stay-wire guide arranged between the strand wires, a knife for cutting stay wires from an advancing length of stay-wire feed, said knife including a blade reciprocating perpendicularly to the plane common to the two strand wires, the said stay-wire guide including a movable member reciprocating in a plane perpendicular to the plane common to the strand wires, and means for moving knife and guide member in synchronism, substantially as described.
7. In a wire-fence machine, in combination with means for feeding a plurality of strand wires in parallel paths, a stay-wire guide arranged between the paths of the strand wires, said guide including two members movable one relatively to the other and adapted by movement to impel one end of a contained stay wire in a direction toward an adjacent strand wire, a reciprocable pusher adapted by movement to impel the opposite end of a stay wire resting in said guide in a direction toward an adjacent strand wire, and means for placing in said guide a severed length of stay wire, substantially as described.
8. In a wire-fence machine, in combination with means for feeding a plurality of strand wires in parallel paths and means for feeding a stay wire diagonally between strand wires advancing in the paths defined, a stay-wire guide arranged between the paths of the strand wires, and consisting of an arched plate having a groove in its upper face, the wall of said groove being movable at a point remote from the crown of the arch of said plate, substantially as described.
9. In a wire-fence machine, in combination with means for feeding a plurality of strand wires in parallel paths, and means for feeding a stay wire diagonally between strand wires advancing in the paths defined, a stay-wire guide arranged between the paths of the strand wires, said guide consisting of an arched plate having a transverse groove in its upper surface, and means for simultaneously engaging from opposite sides the opposite ends of a stay wire resting in said groove and turning it upon the crown of the arch of said plate, substantially as described.
10. In a wire-fence machine, the combination of means for impelling a plurality of strand wires in parallel paths, a stay-wire guide adapted to receive and support a stay-wire with ends extending on opposite sides of strand wires so impelled, means for bringing a stay wire into such position in said guide, said guide being formed of two parts pivoted one upon the other, means for pushing upon one end of a stay wire supported in said guide, means for operating said pusher, and means for swinging the pivoted portion of said guide, the several means defined operating in synchronism, substantially as described.
11. In a wire-fence machine, means for feeding a plurality of strand wires in parallel paths, a stay wire guide including a transversely movable member mounted between adjacent paths of strand-wire feed, a bar carrying a plurality of coilers movable longitudinally of the paths of strand-wire feed, said bar in its movement engaging and effecting movement of the movable member of the stay-wire guide, together with means for feeding a stay wire to said guide, substantially as described.
12. In a wire-fence machine, the combination of means for feeding a plurality of strand wires in parallel paths and in a common plane, a beam extending transversely of the common plane of strand-wire feed and reciprocable in the direction of said feed, a second beam extending transversely of the common plane of strand-wire feed and reciprocable in a direction perpendicular to said plane and capable of being tipped in a direction transverse to its length, a stay-wire feed, a stay-wire guide arranged be-

tween adjacent strand-wire paths and including a movable member, coilers borne by the beam first named, and a stay-wire cutter borne by the second beam, the beam first named being adapted in its reciprocation to effect the shifting of the movable member of said stay-wire guide, and means for shifting said beams and for tipping the second-named beam, such means operating to effect

correlation of the several movements, substantially as described.

In testimony whereof I have hereunto set my hand.

JOHN A. HOLMQUIST.
